US0D1064747S

(12) **United States Design Patent** (10) Patent No.: **US D1,064,747 S**
(45) Date of Patent: ** Mar. 4, 2025

(54) **BOTTLE**

(71) Applicant: **Air up group GmbH**, Munich (DE)

(72) Inventors: **Tim Jaeger**, Munich (DE); **Alexander Jantschke**, Unterfoehring (DE)

(73) Assignee: **AIR UP GROUP GMBH** (DE)

(**) Term: **15 Years**

(21) Appl. No.: **35/517,408**

(22) Filed: **May 10, 2023**

(80) **Hague Agreement Data**

Int. Filing Date: **May 10, 2023**

Int. Reg. No.: **DM/229089**

Int. Reg. Date: **May 10, 2023**

Int. Reg. Pub. Date: **Jun. 2, 2023**

(51) **LOC (15) Cl.** 07-01

(52) **U.S. Cl.**

USPC **D7/511**; D9/452; D24/197

(57) **CLAIM**

The ornamental design for a bottle, as shown and described.

DESCRIPTION

1. Bottle

Fig. 1.1 is a perspective view of a bottle showing our new design;

Fig. 1.2 is a left side elevation view thereof;

Fig. 1.3 is a right side elevation view thereof;

Fig. 1.4 is a front elevation view thereof;

Fig. 1.5 is a rear elevation view thereof;

Fig. 1.6 is a top plan view thereof; and

Fig. 1.7 is a bottom plan view thereof.

The portions of the bottle shown in broken lines form no part of claimed design.

1 Claim, 7 Drawing Sheets
